UNITED STATES PATENT OFFICE.

ERNEST C. ROLFE, OF BELLEVILLE, ILLINOIS.

TROLLEY-WHEEL.

SPECIFICATION forming part of Letters Patent No. 725,485, dated April 14, 1903.

Application filed July 8, 1902. Serial No. 114,715. (No model.)

To all whom it may concern:

Be it known that I, ERNEST C. ROLFE, a citizen of the United States, residing at Belleville, in the county of St. Clair, State of Illinois, have 5 invented new and useful Improvements in Trolley-Wheels, of which the following is a specification.

My invention consists of an improvement in a trolley-wheel embodying a swivel of novel 10 construction for permitting the bearings of said wheel to yield to irregularities of the conductor and a change of direction due to curves, thus preventing the wheel from jumping the conductor, the members of said swivel being 15 also connected by a resilient device, which will relieve said members of severe strain, and other features are presented, as hereinafter described, and the novelty being pointed out in the claims.

20 It also consists in providing ball-bearings for the wheel in order to reduce the friction between the support of the same and the adjacent portion of the pole connection.

Figure 1 represents a side elevation of a 25 trolley-wheel embodying my invention. Fig. 2 represents a vertical section thereof. Fig. 3 represents a horizontal section on line $x-x$, Fig. 2. Fig. 4 represents a horizontal section on line $y-y$, Fig. 1. Fig. 5 represents a horizontal section showing a spring for returning the trolley-head to its central position. Fig. 6 represents a side elevation thereof.

Similar letters of reference indicate corresponding parts in the figures.

35 Referring to the drawings, A designates a trolley-wheel, and B designates ears on which the same is mounted, said ears rising from the sleeve C, within which is the collar D, it being noticed that said sleeve is rotatably 40 mounted on said collar and freely encircling the same. Connected with said collar, at the center thereof, is the stem E of a trolley-pole, which may be fitted in a socket at the upper end of a trolley-pole and secured thereto or 45 constituting a portion of said pole.

F designates a journal which is connected with the collar D and extends upwardly therefrom and passes freely through the upper wall G of the sleeve C. In said journal above said 50 wall is a fastening key or pin H, which, as is evident, connects said sleeve and collar and prevents separation of the same, while, how-

ever, permitting the rotary or swiveling motions of said sleeve on said collar, said key, which is resilient in its nature, causing friction of the wall or head G of the trolley, so as to prevent improper vibrations of the latter, while also presenting a resilient connection for the members of the swivel, said key resting upon a washer which is seated on the 60 top of the wall or head G, by which means the members of the swivel are prevented from disconnection, while said key is not liable to be displaced by the vibratory motions of said head. A portion of the side wall of the sleeve C is cut 65 away, forming the recess J, with shoulders J' at the ends thereof, and projecting from the collar D is the finger K, which freely occupies said recess within the shoulders thereof. The recess J is open from below, whereby 70 when the journal or axle F is introduced into the wall G said finger K occupies its position in said recess J. This permits of said finger K to be an integral portion of the collar D and does not require to be removed from said 75 collar should it be necessary to dismember the parts of the swivel. In the upper side of the collar D and under side of the wall H of the sleeve C are circular grooves L, forming together the race M, in which are placed the 80 balls N, thus forming ball-bearings for said sleeve on said collar, and vice versa.

It will be seen that when the trolley is in use the wheel may operate as usual, but is permitted to yield in lateral direction due to 85 irregularities in the length of the electric wire or conductor and running around curves, the sleeve oscillating or vibrating on the collar, limited by the contact of either of the shoulders J' with the finger K, the wheel thus 90 conforming to said wire or conductor, and so is prevented from jumping the latter or otherwise disengaging therefrom. Any suitable spring or means may be connected with the opposite members of the swivel, so as to return the head to its central position.

Owing to the ball-bearings the motions of the sleeve on the collar are easy and comparatively noiseless, and the friction between said collar and sleeve is vastly reduced, the effect 95 of which is evident.

Having thus described my invention, what I claim as new, and desire to secure by Letters Patent, is—

1. In a trolley-wheel, a support therefor, a connection with the pole thereof, and a swivel-joint intermediate of said pole and support, said joint consisting of an axle which is adapted to be connected with the trolley-pole and passing freely through said support and projecting above the latter, a washer on said support freely encircling said axle and a pin passing through said axle above said washer.
2. In a trolley-wheel, a collar on the trolley-pole, a wheel-support, a plate at the base of said support having an opening therein, a sleeve depending from said base-plate and freely encircling said collar, an axle rising from said collar passing freely through said base-plate and a fastening on said axle above said base-plate.
3. In a trolley-wheel, a collar connected with the trolley-pole, a support for the wheel, a plate at the base of said support having an
- opening therein, a recessed sleeve depending from said base-piece and freely encircling said collar, a projection on said collar occupying the recess of said sleeve, an axle rising from said collar passing freely through the base-piece of the wheel-support and a fastening-pin on said axle above said base-piece.
4. In a trolley-wheel, a support therefor, a connection with the pole thereof, and a swivel-joint intermediate of said pole and support, said joint consisting of an axle which is adapted to be connected with the trolley-pole and passing freely through the base of said support and projecting above said base, and a resilient pin passing through said axle.

ERNEST C. ROLFE.
